UNITED STATES PATENT OFFICE.

RAY P. VASTINE, OF CHICAGO, ILLINOIS, ASSIGNOR TO GEORGE M. VASTINE, OF CHICAGO, ILLINOIS.

VIEW PASSAGE FOR FURNACES.

Application filed October 31, 1924. Serial No. 746,862.

This invention relates to a device for permitting the surface of the fire in a furnace to be viewed from outside the same without necessitating the opening of any doors or 5 closures.

In furnaces of various types it is particularly desirable to view the fire on the grate from time to time in order to ascertain by its appearance whether or not there are any 10 dull spots, clinkers, etc., or whether or not it is burning properly.

Previous to this time no device has been found practicable which will permit such a view without necessitating the opening of a 15 door or a peep hole with the resulting cold draft on the fire and loss in efficiency or in the case of forced draft furnaces the resulting flare of heat out through the opening which represents a material heat loss and in 20 addition may cause serious injury or discomfort to individuals near the openings. Ordinarily no transparent material such as glass will stand the high heat of the furnace in order to permit its use in a device of this 25 kind so that heretofore this has been the chief obstacle to such a device.

It is therefore the object of this invention to provide a device of this kind in which the 30 heat is so reduced near the exterior of the opening permitting such a view that glass or similar substance may be used in said opening for the closure thereof.

More broadly it is the object of this invention to provide a device which will permit 35 a view to be had of the entire surface of the fire on the grate without opening any passage to the furnace.

It is further the object of this invention to provide a passage in the side of the furnace 40 having a flare in its outer end for permitting a maximum view of the grate and for diminishing the intensity of heat radiation to the outer end of said passage and to provide an air circulation around said passage 45 sage to assist in reducing the heat therein.

It is also an important object of this invention to provide a passage in the side of the furnace for viewing the fire in which the intensity of heat radiation therethrough is 50 reduced gradually towards the outer end thereof by the use of transparent screens situated at intervals across said passage.

It is also an important object of this invention to provide a view passage to the 55 furnace in which the heat is so reduced in

the outer end of said passage as to permit the use of a transparent substance such as glass to completely close the outer end.

It is further an object of this invention to provide a passage of this kind in which glass 60 or similar material is used to close the outer end thereof.

Other and further important objects of this invention will be apparent from the disclosures in the specification and the accompanying drawings. 65

This invention (in a preferred form) is illustrated in the drawings and hereinafter more fully described.

On the drawings:

Figure 1 is a direct front view of a device embodying principles of the present invention:

Figure 2 is a fragmentary central vertical sectional view showing the device mounted in the wall of a combustion chamber or the like. 75

Figure 3 is a reduced view similar to Figure 2 but showing the device in elevation.

Figure 4 is a plan sectional view of the device taken substantially along line IV—IV of Figure 3. 80

Figure 5 is a side view of the device in a horizontal position, showing the outer casing in central vertical section, and the inner 85 casing in elevation.

Figure 6 is a vertical sectional view taken substantially along the line VI—VI of Figure 5.

As shown on the drawings:

Numeral 1 represents the side of the furnace which in this case is a brick wall. It will be noted that the wall has an inclined aperture therethrough for receiving a ribbed casing 2. The casing 2 has a plurality of 95 longitudinal ribs thereon for resisting the conductivity of heat from the wall to said casing. As shown by Figure 4 the casing 2 has a wide longitudinal flare at its outer end. This flare both reduces the intensity of the 100 radiation of heat from the furnace to the outer side of the passage within the casing 2 and also increases the view obtainable from said outer side. Secured to the casing 2 are securing members 3 for securing the casing 105 to the wall 1. Enclosed within the casing 2 is an inner casing 4 which is flared in a manner similar to the outer casing 2.

Within the inner casing 4 which forms a view passage to the furnace are a plurality 110

of screens or grids 5 situated across the passage and spaced at intervals throughout the length thereof. The screens 5 are preferably of cast iron of a mesh which is of increasing fineness toward the outer end of the passage to effectually minimize the radiant transference of heat therethrough.

The inner casing 4 and the outer casing 2 form therebetween an air chamber having an inlet 6 in the lower side of the outer casing and an outlet through the funnel 7 on the upper side of said casing. A plurality of longitudinal ribs or webs 8 (as seen in Figure 5) in said air chamber provide a tortuous passage for the air circulating therein which increases the thermal conduction through the walls of the casing, thereby diminishing the thermal radiation outwardly. Hinged to the outer casing 2 at the outer end thereof is a frame 9 having rigidly secured thereto outer and inner supporting members 10 and 11 for outer and inner panes 12 and 13. A circulation of air is provided between said panes by means of a plurality of holes 14 therebetween in the lower side of the frame 9 and an aperture 15 in the inner supporting member 11. By using a plurality of pane sections as shown in Figures 1 and 4 to make up the panes 12 and 13 cracking of the pane which might happen in using a single large piece is prevented.

In the use of this device it will be seen that a clear view of the surface of the fire is obtainable at all times whereas it has previously been necessary to open the furnace door or a peep hole, necessitating a material loss in efficiency as well as exposure to a flareback. This device is also adapted to be used in oil burning furnaces where it is necessary to observe the burner frequently to determine whether a proper efficient combustion is being obtained. In oil burning furnaces which always operate under forced draft the danger due to flareback is very great especially when not operating under the closed fireroom system. By the use of the screens 5 the heat radiated toward the glass panes 12 and 13 is greatly decreased. This heat is further decreased by the outward flare of the passage. The heat of conductivity is decreased by the tortuous air passage and circulation therethrough between the inner casing 4 and the outer casing 2. This heat is further decreased by the air surrounding the outer casing 2 between the ribs thereon. The air circulation between the two transparent panes 12 and 13 further decreases the temperature thereof. Without these heat reducing means it would be impossible to use glass or similar substance as a means for closing the view passage.

I am aware that many changes may be made and numerous details of construction may be varied through a wide range without

departing from the principles of this invention and I therefore do not purpose limiting the patent granted hereon, otherwise than necessitated by the prior art.

I claim as my invention:

1. In a device of the class described, a tubular casing, a plurality of graduated screens across the interior of said casing, said screens being progressively graduated with respect to their areas, and a transparent member closing the outer end of said casing. 70

2. In a device of the class described, a casing, a second casing within said first mentioned casing forming an air chamber so therebetween, said air chamber being closed at the inner end of said casings, and ribs on the exterior of one of said casings. 75

3. In a device of the class described, a tubular casing, a plurality of screens across the interior of said casing, and progressively graduated with respect to their planar areas, and a transparent pane member closing said casing, said casing having an outward flare toward the exterior thereof. 90

4. The combination with a combustion chamber having an opening therein, a plurality of spaced transparent observation closures for said opening in constant exposure to the thermal radiation from said combustion space, and means for insuring against destruction of said closures due to the constant thermal exposure thereof, said means including a plurality of grids positioned in said opening and graduated with respect to their planar areas. 95

5. The combination with a combustion chamber having an opening therein, a plurality of spaced transparent observation closures for said opening in constant exposure to the thermal radiation from said combustion space, and means for insuring against destruction of said closures due to the constant thermal exposure thereof, said means including a plurality of spaced and apertured grids in said casing, each of said grids except one having larger apertures than the grid adjacent one side thereof to enhance the vision through said opening. 105

6. The combination with a combustion chamber having an opening therein, a pair of hinged transparent closures for said opening, and means for diminishing the thermal radiation to said closures, said means including means permitting the passage of air between said closures, and a plurality of screens transversely disposed within said opening, the meshes of said screens being of increasing fineness toward said closures. 115

7. In a furnace fire observer, a casing, a second casing therein, staggered webs between said casings providing a circuitous air passage therebetween, said passage being closed at the inner end of said observer. 125

8. In a device of the class described, an 130

outer casing having longitudinal ribs thereon, an inner casing, staggered webs between said casings providing a tortuous air passage therebetween, and apertured plates extending across said inner casing.

9. A furnace fire observer comprising a casing, a transparent closure associated with the outer end of said casing, and a plurality of plates extending across said casing, said plates having graduated apertures therein, each rearwardly disposed plate having larger apertures than its adjacent forwardly disposed plate.

10. A furnace fire observer comprising an inwardly converging casing, a transparent closure for said casing, and a plurality of transverse plates graduated with respect to their planar areas in said casing and having apertures therein, said apertures being sized in inverse proportion to the area of said plates.

11. In a device of the class described, an inwardly converging casing, a pair of hinged transparent closures for the outer end of said casing, and means to protect said closures from exposure to high temperature, said means comprising a plurality of transversely disposed apertured grids positioned in said casing, said grids being progressively graduated with respect to their planar areas, the apertures in said grids being sized in

inverse proportion to the areas of said grids, the smaller of said grids being the innermost and having the largest apertures therein.

35

12. In a device of the class described, an outer casing, an inner casing spaced from said outer casing to provide an air passage therebetween, said passage being closed at the inner end of said casings, said outer casing having an entrance to and exit from said passage adjacent its outer end.

13. In combination, a combustion chamber enclosure having an aperture therethrough, a casing partially within and spaced from the walls of said aperture, a closure for said casing, there being means for admitting air through said aperture to increase the thermal conduction through said casing, and said casing having means for admitting air through the interior of said casing to diminish the thermal radiation from said combustion chamber.

14. In a device of the class described, a plurality of substantially nested casings, an integral rim on one of said casings, and an observation closure for one of said casings hinged to said rim.

In testimony whereof I have hereunto subscribed my name.

RAY P. VASTINE.
